UNITED STATES PATENT OFFICE

MIRIAM T. SIMON, OF NATCHEZ, MISSISSIPPI

PROTECTOR FOR TOILET SEATS

Application filed August 18, 1931. Serial No. 557,848.

This invention relates to sanitary covers for toilet seats and it has for its general object the provision of a seat cover adapted to individual use, formed of paper or the like, and preferably of such character that it readily disintegrates in water so that it can be advantageously disposed of after use without risk of obstructing the plumbing.

One of the more specific objects of the invention is to provide a seat cover of the type indicated which while normally flat, conforms to the inner edge of the seat aperture under the weight of the sitter, without the development of tears or fissures in the concaved margin, thus ensuring complete protection from contact with the seat edges.

Another object of the invention is to provide the seat cover in the form of a flexible sheet folded at a plurality of places to form pleats, said pleats being pasted together for a portion of their length but left free adjacent the margin of the aperture in the seat cover whereby to impart fullness to the latter, permitting it to conform to the edges of the hole in the seat without tearing, while the pasted down portions form reinforcing strips, assisting the seat cover which is made of more or less flimsy material, to lie flat upon the seat.

Still another object of the invention is to provide a seat cover, the forward edges of which shall extend beyond the seat sufficiently to be grasped and folded under the seat by raising the latter and then placing the seat down upon the underlying corners so that the seat cover is held firmly in place.

Another object of the invention is to provide a seat cover normally in flat shape so that it may be conveniently packaged for vending in coined controlled apparatus.

Other objects of the invention will appear as the following description of a preferred and practical embodiment thereof proceeds.

In the drawing in the several figures of which the same characters of reference have been used throughout the several figures to designate identical parts:

Figure 1 is a perspective view showing the seat cover in place;

Figure 2 is a plan view of the seat cover in flat condition;

Figure 3 is a cross section through a portion of a toilet seat showing the seat cover with the forward corner tucked under the seat and the marginal portion surrounding the aperture being pressed into conformation with the edge of the hole in the seat;

Figure 4 is a section taken along the line 4—4 of Figure 3;

Figure 5 is a section taken along the line 5—5 of Figure 2; and

Figure 6 is a section taken along the line 6—6 of Figure 2.

Referring now in detail to the several figures, numeral 1 represents the sheet preferably of tissue material, such as undressed paper, of such nature that it will readily disintegrate in water. It may be of any desired shape but is here shown as rectangular and being folded upon itself at the three places where indicated to form pleats 2. It is immaterial how many pleats are formed but the folds should extend from the outside edge of the sheet to the periphery of the central aperture 3. In common with other known seat covers that of the present invention is provided with a forward flap 6 adapted to extend within the front portion of the seat aperture.

The pleats 2 are pasted together for a portion of their length as is indicated at 4, but the inner portions of said pleats adjacent the margin of the sheet which surrounds the aperture 3 are left free as is clearly shown at 5 in Figure 4, so as to permit the said marginal edge to expand as it is deflected inwardly into conformation with the hole in the seat under the weight of the sitter, preventing its becoming torn.

As it is well understood that the material of which the seat cover is made, is quite flimsy, the pasted portions of the pleat act as reinforcing strips to assist in the placing of the sheet flat upon the toilet seat.

The forward corners 7 and 8 preferably extend sufficient distance forwardly of the toilet seat so that they may be turned down, and by lifting the toilet seat a trifle tuck under its forward edge without the fingers coming in contact with the seat. When the

toilet seat is let down the corners 7 and 8 are held firmly, preventing the seat cover from slipping out of place.

- Seat covers having the marginal portion which surrounds the aperture pre-molded so as to conform to the seat are known, but such covers cannot be folded into small packages and are therefore too unwieldy for individual distribution and use. It is also known to provide flat flexible seat covers, folded so that they may be vended from dispensing machines but the marginal portions of such covers split when sat upon, bringing the body into contact with the portions of the seat exposed through the torn places. The seat cover of the present invention has the advantage that it may be folded into a perfectly flat and compact package adapted to automatic vending machines and at the same time so constructed as to avoid the risk of splitting of the inner marginal portion.

While I have in the above description, disclosed what I believe to be a preferred and practical embodiment of the invention, it is to be understood that such changes may be made in the construction and arrangement of the parts as are permitted by the breadth of the appended claim.

What I claim is:

1. Protective cover for toilet seats comprising a flat flexible sheet adapted to overlie the toilet seat and having an aperture adapted to register with the hole in the said seat, said sheet being folded at a plurality of points forming pleats terminating at the edges of said aperture, the outer portions of said pleats being secured to prevent spreading of the outer portions with consequent elongation of the aperture, the inner portions of said pleats being left free to give fullness to the marginal portion of said sheet surrounding said aperture.

In testimony whereof I affix my signature.

MIRIAM T. SIMON.
